Primary Examiner — John Windmuller

(74) Attorney, Agent, or Firm — Abel Schillinger, LLP;
Thomas H. Osborn(57) **CLAIM**

The ornamental design for an attachment piece, as shown and described.

DESCRIPTION

FIG. 1 is a front perspective view of an attachment piece;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines showing a portion of the attachment piece are for illustrative purposes only and form no part of the claimed design.
